MICROFILMER BASE

Frank A. Zagara, Rochester, N.Y., assignor to Eastman Kodak Company, Rochester, N.Y., a corporation of New Jersey

Filed Jan. 29, 1960, Ser. No. 59,197

Term of patent 14 years

(Cl. D61—1)

FIG. 2

FIG. 3

FIG. 1 is a perspective view of a microfilmer base showing my new design, with a film unit, therefor, shown in broken lines for purposes of illustration;

FIG. 2 is a perspective view showing the rear thereof; and

FIG. 3 is a fragmentary cross-sectional taken along line 3-3 in FIG. 2.

I claim:

The ornamental design for a microfilmer base, as shown.
